(57) **CLAIM**

The ornamental design for a cockpit door interior, as shown and described.

DESCRIPTION

FIG. 1 is a front view showing our new design of a cockpit door interior;

FIG. 2 is a forward perspective view of the cockpit door interior of FIG. 1;

FIG. 3 is a rear perspective view of the cockpit door interior of FIG. 1;

FIG. 4 is a top perspective view of the cockpit door interior of FIG. 1;

FIG. 5 is a bottom perspective view of the cockpit door interior of FIG. 1;

FIG. 6 is a perspective view from within an aircraft cockpit of the cockpit door interior of FIG. 1; and,

FIG. 7 is a front view from within an aircraft cockpit of the cockpit door interior of FIG. 1.

The broken lines in FIGS. 1-7 illustrate portions of the cockpit door interior that form no part of the claimed design.
